UNITED STATES PATENT OFFICE

JOHN A. FILBERT, OF CHICAGO, ILLINOIS

GRATE CONSTRUCTION

Application filed December 28, 1928. Serial No. 329,041.

This invention relates to certain novel improvements in grate constructions, and has for its principal object the provision of an improved construction of this character which will be highly efficient in use and economical in manufacture.

It is among the objects of my invention to provide a grate construction which will be arranged such that it may be formed in sections that may be arranged in any desired relation so as to form the entire grate floor in a boiler or similar coal burning apparatus, although it is to be understood that my invention is not necessarily limited to the burning of coal since any other analogous fuel may be used in connection therewith.

It is another object of my invention to provide a great construction which will embody an arrangement whereby the fire may be expeditiously dumped from the grate.

A further object of the invention is to arrange the grate in such a manner that it will embody means whereby clinkers and other undesirable formations may be broken up.

A still further object of the invention is to provide a device of the above named character wherein the fire may be agitated or shaken when so desired.

A still further object of the invention is to provide a device of the above named character in such a manner that the clinker breaking apparatus may be actuated independently of the shaking and dumping apparatus.

A still further object of the invention is to provide a grate which will be arranged in such a manner that a portion thereof may be broken off or rendered inactive in order that the intensity of the fire and the fuel consumption may be reduced under certain conditions, as in mild weather.

A still further object of the invention is to provide a grate construction in which draft may be expeditiously controlled.

Other and further objects will appear hereinafter.

The invention consists in the novel combination and arrangement of parts to be hereinafter described and claimed.

The invention will best be understood by reference to the accompanying drawings

wherein a preferred form of construction is shown, and in which:

Fig. 1 is a plan view of a preferred form of construction for my device;

Fig. 2 is a side elevational view in which certain parts are broken away of the mechanism illustrated in Fig. 1;

Fig. 3 is a longitudinal sectional view of a preferred form of construction of my device depicting the parts shown in Figs. 1 and 2;

Fig. 4 is a view substantially similar to Fig. 3, depicting the clinker breaking mechanisms in slightly elevated position;

Fig. 5 is a view similar to Fig. 4 depicting the shaking and dumping mechanisms in dumping position;

Fig. 6 is a transverse sectional view of the mechanism illustrated in Figs. 1 and 2;

Fig. 7 is a perspective detail view of a member employed to close off the section of the grate;

Fig. 8 is a bottom plan view;

Fig. 9 is a detail view depicting a latch mechanism employed in the device;

Fig. 10 is a sectional detail view taken substantially on the line 10—10 on Fig. 9; and

Fig. 11 is a view substantially similar to Fig. 9 depicting the parts in released position.

In the drawings, wherein I have illustrated the preferred form of construction for my device, 10 generically indicates the main frame of my device which includes side members 11 and 12 and end members 13 and 14, 85 the end member 14 being in the form of a substantially flat plate in the present instance, although in constructing the device for arrangement interiorly of a boiler wherein a plurality of the frame members 10 will be employed the end member 14 will consist of a strip substantially similar to the end member 13 and the plate member 14 will be disposed extraneous the furnace which is the position intended in the present construction.

In the present instance the side members 11 and 12 have a plurality of notches 15 provided therein which comprise relatively narrow slots terminating in rounded portions 100

at the inner ends thereof. The shaking and dumping members 16 have pin members 17 provided on the ends thereof which include flattened portions 18. In assembling the device the shaking members are arranged in a position such that the flattened portions on the pin members 17 may be passed through the relatively narrow outer portions of the slots 15 and after the parts have been inserted the dumping members 16 are then disposed such that the flattened portions 18 are arranged such that passage back through the narrow portions is prevented; that is, when the rocking members 16 are disposed in operative position the pin members 17 are then disposed in the rounded portions of the notches 15.

Depending downwardly from the dumping members 16 adjacent the side edges thereof are bearing members or bosses 19 and 20. In the lower portion of the bearing members 19 enlarged bearing portions 21 are provided which have passages 22 extending therethrough. Pin members 23 are extended through the passages 22 for a purpose to be set forth presently. Extending along so as to interconnect the various bearing members 19 on the outwardly disposed faces thereof is a bar 24. In a similar manner, bearing blocks 25 are provided in the lower ends of the bearing members 20 which have passages 26 extending therethrough in which pins 27 are mounted. The plates 28 are disposed on the outwardly disposed faces of the bearing members 20 and have openings therein in which pins are extended and cotter pins 29 or analogous devices are employed for preventing displacement of the bars from the pins. Similarly, the pins 23 extend through openings in the bars 24 and cotter pins 30 prevent displacement of these bars from the pins.

On the inwardly disposed faces of the bearing portions 21 link members 31 are arranged and the pin members 23 are extended through openings in these link members. These links 31 are retained in position through the medium of cotter pins 32 or analogous devices. Similarly, links 33 are arranged in abutment with the inner faces of the bearing blocks 25 and the pins 27 are extended therethrough and said links are held on said pins through the medium of cotter pins 34 or analogous devices.

As best illustrated in Fig. 1, the dumping members 16 have longitudinally extending or stem slots 35 provided therein. Branching out from the slots 35 are transversely extending or branch slots 36. The clinker breaking members generically indicated by 37 include an elongated portion 38 adapted to be disposed in the slot 35 from which branch elements 39 extend so as to be disposed in the branch slots 36, the clinker breaker means being thus arranged in "trees". Depending

downwardly from the clinker breaking members 37 are substantially U-shaped portions 40 and 41. A link member 42 is pivotally connected in the portion 40 and the link member 43 is pivotally connected in the U-shaped portion 41. As clearly illustrated in Figs. 3 and 4 the free ends of the links 42 and 31 are pivotally connected together as indicated at 44. Similarly, the free ends of the links 43 and 33 are pivotally connected together as indicated at 45 (Fig. 2). Intermediate the ends of the link 42 one end of a link 46 is pivotally attached. Intermediate the ends of the link 31 a link 47 is pivotally attached. A bar 48 extends between the various pivotal connections 44 and is pivotally connected at these points 44. A bar 49 extends between the various pivotal connections 45 and is pivotally connected at these points. A bar 55 is provided and is pivotally connected to the pivotally connected ends of the links 46 and 47. A bar 56 is pivotally connected to the free ends of the links 57 and 58 which correspond to the links 46 and 47. The bars 55 and 56 are arcuate so as to embody a downwardly directed contour in the portions thereof between the pivotal connections, for a purpose to be set forth hereinafter.

An operating member generically indicated by 52 and best shown in Fig. 8 is provided that includes a substantially U-shaped inner end portion that includes arms 53 and 54. The arms 53 and 54 have their inner end portions pivotally connected to inwardly extending studs 50 and 51 that are carried on the bars 48 and 49. A member 59 is provided which includes a substantially U-shaped inner end portion that comprises arms 60 and 61. The inner ends of the arms 60 are pivotally connected at one of the pivotally connected points of the arm 55 and the arm 61 is preferably pivotally connected at a corresponding pivotally connected point of the arm 56. The member 59 preferably has a relatively small movement imparted thereto in a manner set forth hereinafter, and the arm 52 is adapted to be moved a relatively great amount as compared to said member 59. When the arm 52 is moved, movement is imparted to the links 42 and 31 from the arm 48 acting through the arm 53 and to the links 33 and 43 through the arm 49 which receives the motion from the arm 54. Inasmuch as the member 59 is intended to be moved only a slight amount, it is apparent that the arms 60 and 61 will move but a small amount. Similarly, the arms 55 and 56 will also move but a small amount. Therefore, the links 46 and 47 and 57 and 58 will tend to pivot about their pivotal connections to these respective arms as the links 42 and 31 and 43 and 33 are moved. Therefore, the angle between the links 42 and 31 and 43 and 33 will be increased or decreased, 123

- which will tend to lower or elevate the members 37 such that they will pass through the openings 35 and 36 relative to the members 16.
- 5 A link 62 is provided which is pivotally connected to the pin member 27 disposed nearest the end construction 14. When movement is imparted to this link member 62 in a manner to be set forth hereinafter, it is apparent that the movement to the first pin member 27 will be transmitted to the remaining pin members 27 through the bar 28. Inasmuch as both the bearing members 19 and 20 depend from the members 16, it is apparent that when movement is imparted to the various members 16 through the bar 28 that the bearing members 19 will also be interconnected through the bar 24 which engages the various pins 23. The movement imparted to the link 62 will be such that it will pivot the members 16 about the studs 17 from the position illustrated in Fig. 3 into the position illustrated in Fig. 5. It is therefore apparent that the grate floor will be disposed at an angle and therefore the fire will be dumped therefrom. When it is desired to shake or agitate the fire, a very slight movement will be imparted to the link 62 in order that the members 16 will be moved but a relatively small amount. At the time the link 62 is moved it is intended that both the members 52 and 59 be released. Therefore, the members 37 and the parts co-operating therewith will move in conjunction with the parts 16. It is therefore apparent that while the members 37 will be movable relative to the members 16, the members 16 are only moved when the parts 37 are moved therewith.
- 10 In order that the foregoing mentioned movements will be properly carried out, I provide the following lever construction. Depending from the plate 14 is a bearing member 63. A stud 64 is provided on the bearing member 63 and a lever 65 is pivotally mounted on the stud 64. The free end of the link 62 is pivotally connected to the lower end of the lever 65 as indicated at 66. Therefore, when a suitable implement is pressed upon the upper end of the lever 65 and the same is rocked about the pivot 64 thereof, the hereinbefore mentioned movement will be imparted to the link 62 which will cause the rocking of the members 16 as set forth.
- 15 Mounted on the upper side of the plate 14 is an arcuate member 67 which has ratchet teeth 68 provided at the inwardly disposed end thereof. Pivotally mounted on the stud 68a carried by the bearing member 63 is a lever 69 the contour of which is best illustrated in Fig. 4. Pivotally mounted adjacent the upper end of the lever 69 is a latch dog 70 which is adapted to engage the ratchet teeth 68 so as to hold the lever 69 against pivotal movement about the stud 68a.

As best illustrated in Fig. 1, the member 67 is adapted to have a centrally disposed slot 71 provided therein through which the lever 69 is adapted to extend. The lever 65 is adapted to move along one side of the member 67. A substantially U-shaped bracket 72 is provided on the member 14 and a latching dog 73 is pivotally mounted therein. The latching dog 73 includes a lip 74 that is adapted to be disposed in front of the lever 65 in order to prevent forward movement thereof and so as to hold said lever 65 at the rear end of the slot 75 of the member 14 through which it extends and when said lever is disposed in this position members 16 will be held substantially horizontal.

The member 52 includes an outwardly directed end portion 76 while the member 59 includes an end portion 77 that corresponds to the end portion 76. On the lever 69 above the pivotal connection thereof 68a and preferably at a relatively great distance therefrom, a pin member 78 is provided in the end portion 76 in which the pin 78 is adapted to be disposed. The slot 79 includes upwardly directed portion 80 that is adapted to be disposed from alignment with the major extent thereof and the pin 78 is normally disposed in this portion. A pin 82 is provided adjacent the lower end of the lever 69 preferably in juxtaposition to the pivotal connection 68a of said lever. A slot 83 is provided in the end portion 77 and includes an upwardly extending portion 84 that is normally disposed from alignment with the major extent of the slot 83 and the pin member 82 is normally disposed in this portion 84.

On the link 87 an enlarged portion or pad 85 is provided. Mounted over the pad 85 is a plate 86 and this plate is secured to the pad by screws 87a. The plate 86 is secured to the lever 69 on the side thereof against which the end portions 76 and 77 bear. Disposed over the end portions 76 and 77 to extend along the lever 69 between the pad 85 and the plate 86 is a bar or arm 87. Lugs 88 and 89 are provided on the face of the bar 87 disposed toward the end portions 76 and 77. The end portion 77 includes a protruding portion 90 and when the end portions 76 and 77 are locked the end portion 90 is disposed between the lugs 88 and 89. Lugs 91 and 92 are provided on the face of the arm 87 disposed toward the end portion 76 and are adapted to receive between them this end portion 76. An L-shaped bracket plate 93 is provided on the arm 87 and a spring member 94 extends between this L-shaped bracket 93 and a securing screw 95 on the plate 86 and serves to hold the arm 87 in a position such that the pin members 82 and 78 are disposed in the notches 84 and 80. Mounted on the segmental member 67 adjacent the forward end thereof is a releasing dog 96. This mounting is accomplished by providing on the releasing

dog 96 bearing portions 97 and 98 about which the member 96 may roll. The upper end of the arm 87 is provided with a hook portion 99. A roller member 100 is provided on the inner end of the member 96 that is normally disposed in the hook portion 99. By depressing the lip portion 101 on the member 96 the member 96 rolls about the bearing 96 and 98 thereof and the roller member 100 engages the hook portion 99 moving the portions 76 and 77 such that the slots 80 and 84 disengage the pins 78 and 82. Therefore, the members 52 and 59 are released and when the lever 65 is manipulated in the manner set forth so as to move the members 16 which obviously moves the members 37 therewith, the end portions 76 and 77 of the members 52 and 59 will be freed to move. The slots 79 and 83 permit the movement relative to the pins 78 and 82. However, when the foot portion 101 is released the spring 95 tends to urge the arm 87 such that the hereintofore mentioned lugs 88, 89, 90, and 91 thereon act on the end portions 76 and 77 such that when the slots 80 and 84 move into proper position they will again re-engage the pins 78 and 82, and thus position the parts in the position depicted in Fig. 9. It has been set forth that the pin 82 is located at a point adjacent the pivoting points 68 of the levers 69 while the pin 78 is preferably positioned a greater distance therefrom. Therefore, when the lever 69 is pivoted about the pivot 68a therefore relative to the arcuate member 67, greater movement will be imparted to the end portion 76 than to the end portion 77, and therefore greater movement will be imparted to the member 52 than to the member 59 for the purpose which has been set forth hereintofore.

I have found it desirable to provide adjacent the end member 14 a member 102 which is intended to be movable in a manner substantially similar to the member 16, but which in place of the openings 35 and 36 merely has a plurality of transversely extending openings 103 provided therein and this member 102 is not provided with clinker breaking construction. In order that the member 102 may be rocked, said member being substantially mounted similar to the member 16, having studs 104 thereon similar to the studs 17, I provide on the under side thereof two lugs 105 which have link members 106 pivotally connected to the lower ends thereof, the other ends of the link members 106 being pivotally connected to the lugs depending from the member 16 juxtaposed thereto in the manner clearly set forth in Fig. 5.

It is apparent that by causing the latch dog 70 to engage different of the teeth 68, the clinker breaking members may be disposed in different positions with respect to the openings 35 and 36. When they are elevated in the manner depicted in Fig. 4 they are in clinker breaking position, but by disposing

these members relative to the openings 35 and 36 and below the upper plane of the member 16 I am enabled to control the amount of space between these members and these openings and thus air passage may be controlled, which will obviously control the draft to the fire and therefore regulate the burning thereof.

As has been set forth, a plurality of the frame members 10 are adapted to be associated with each other to provide a grate for a boiler. In mild weather it is sometimes desirable that a portion of the grate be blocked out so as to prevent burning thereabove and thus conserve fuel. In order to accomplish this, I provide members 107 which are clearly depicted in Fig. 7 and which include a downwardly depending rib 109 that is adapted to be disposed in the opening 35 when the member 107 is disposed above the rockable member 16. Branch arms 110 are provided which correspond to the openings 36. By disposing the member 107 such that the rib 108 is disposed in the openings 35 the portions 109 and 110 thereof will serve to close the openings 35 and 36 and thus prevent passage therethrough. In order to dispose these members 107 in position the members 37 are moved into their lowermost position and the members 107 may be positioned through the usage of a hook in a manner well understood in the art. In order to displace the members 107 the members 37 are moved into their uppermost position which obviously forces the members 107 from position in the openings 35 and 36, and they may be then withdrawn from the fire box through the employment of a hook as is well understood. It is apparent that as many of the members 107 as desired may be employed so as to block out a portion of each of the openings 35 and 36 in each of the frame members 10 or if desired all of the openings in a given section of the frame members 10 may be blocked out.

If desired a notch 111 (Fig. 4) may be provided in the segmental member 67 which is adapted to be engaged by the foot portion 112 of the latch member 70 so as to hold the members 37 in their lowermost position.

It is apparent from the foregoing description that I have provided a grate construction which is arranged such that a plurality of sections may be provided so as to provide a grate construction of any desired size. Further, I have arranged this grate construction such that the fire may be expeditiously agitated or shaken, and may be dumped when so desired. Further, I have provided a construction which will break up clinkers or other undesirable formations and also a construction in which the draft may be expeditiously controlled. Further, by arranging certain of the members of my device in a predetermined position, the floor of the grate may be made substantially closed so as to pre-

5 vent the falling of fire or particles of fuel therethrough as occurs when the fire is first started. It is apparent that the device may be easily manipulated and is arranged such that the control thereof may be entirely carried out extraneous of the fire box with which it is associated. Further, the device is arranged such that a portion of the grate may be blocked off so as to reduce the fuel con-
10 sumption when desired.

15 While I have illustrated and described the preferred form of construction for carrying my invention into effect, this is capable of variations and modifications without departing from the spirit of the invention. I, therefore, do not wish to be limited to the precise details of construction set forth, but desire to avail myself of such variations and modifications as come within the scope of the ap-
20 pended claims.

Having thus described the invention, what I claim as new and desire to protect by Letters Patent is:

25 1. A grate construction comprising a frame, a plurality of dumping members in said frame, said dumping members having longitudinally extending slots provided therein and branch slots extending therefrom, clinker breaker means normally disposed below said slots and movable relative to and through said slots, link constructions pivotally connected to said means, and means for imparting movement to said link constructions whereby said clinker breaker means will be moved through
30 said openings in a substantially vertical plane.

35 2. In a grate construction, a frame, a plurality of rockable members mounted in said frame, said rockable members having lugs depending therefrom, means for interconnecting the lugs depending from the respective rockable members, means for imparting movement to said connecting means whereby said rockable members may be rocked, said
40 rockable members having openings provided therein, means movable with said rockable members for closing said openings, means for operating said last named means including link members pivotally connected thereto,
45 and other link members pivotally connected to said movable means, means for interconnecting the free ends of said last mentioned link members, a link member pivotally connected to said first named link members in-

50 termediate the ends thereof, a link member pivotally connected to said second named link members intermediate the ends thereof, means for pivotally connecting the free ends of said last named link members, and means
55 for imparting movement to said link members connected to said link members at the pivotal connections of the free ends thereof.

60 3. A grate construction including rockable members having openings provided therein, members movable relative to said rockable

members through said openings, link members pivotally connected to said last named members, said rockable members having bosses depending therefrom, other link members pivotally connected to the lower ends of said bosses, means for pivotally connecting the free ends of said link members, an operating member pivotally connected to the said link members at the pivotal connections of the free ends thereof, other link members pivotally connected to said first named link members, means for pivotally connecting the free ends of said last named link members, a second operating member connected to said last named link members at the pivotal interconnections thereof, a pivotally mounted lever, means for connecting the free ends of said operating members to said lever to cause greater movement to be imparted to said first named operating member than to said second operating member.

4. A grate construction including rockable members having openings provided therein, members movable relative to said rockable members through said openings, link members pivotally connected to said last named members, said rockable members having bosses depending therefrom, other link members pivotally connected to the lower ends of said bosses, means for pivotally interconnecting the free ends of said link members, an operating member pivotally connected to said link members at the pivotal connections of the free ends thereof, other link members pivotally connected to said first named and second named link members, means for pivotally connecting the free ends of said last named link members, a second operating member connected to said last named link members at the pivotal connections thereof, a pivotally mounted lever, means for connecting the free ends of said operating members to said lever to cause greater movement to be imparted to said first named operating member than to said second operating member, said connecting means being so arranged that said operating members may be detached from said lever whereby said operating members may be moved relative to said lever.

5. In a grate construction, a frame, a plurality of dumping members pivotally mounted on said frame, each having a longitudinally extending slot provided therein and branch slots extending from both sides thereof, clinker breaker means for each of said members, each of said means consisting of a main longitudinal stem with branch projections extending from both sides thereof, normally disposed below and corresponding with said slots, tilttable with said dumping members, and movable upwardly through and above said slots, means including slide bar and link structures for tilting said dumping members, and means for moving said clinker breaker means vertically through said slots.

6. In a grate construction, a plurality of dumping members each having a longitudinally extending stem slot and branch slots on both sides thereof, means for tilting said dumping members, and means each including portions adapted to project over and close said branch slots and each including a portion removably insertible into one of said stem slots so that the last-named means may be supported by, and render inactive, a predetermined number of said dumping members.
7. In a grate construction, a plurality of dumping members each having a longitudinally extending stem slot and branch slots on both sides thereof, means for tilting said dumping members, clinker breaker means normally disposed below, and movable through said slots and tiltable with said dumping members, and means each including portions adapted to project over and close said branch slots and each including a portion removably insertible into one of said stem slots so that said last-named means may be supported by, and render inactive, a predetermined number of said dumping members.

In testimony whereof I affix my signature.
JOHN A. FILBERT.
